(57) **CLAIM**

The ornamental design for a golf shoe, as shown and described.

DESCRIPTION

FIG. 1 is a top perspective view of a golf shoe showing our new design;

FIG. 2 is a lateral side elevation view thereof;

FIG. 3 is a top plan view thereof;

FIG. 4 is a medial side elevation view thereof;

FIG. 5 is a bottom plan view thereof;

FIG. 6 is a front elevation view thereof;

FIG. 7 is a rear elevation view thereof; and,

FIG. 8 is a bottom perspective view thereof.

The dashed-dot-lines on the shoe represent thread stitching and the even-dashed broken lines on the shoe represent unclaimed subject matter that form no part of the claimed design.
